UNITED STATES PATENT OFFICE.

HENRY GIBSON O'NEILL, OF NEW YORK, N. Y., ASSIGNOR OF TWENTY-NINE THIRTY-SECONDS TO JOHN ROONEY, OF SAME PLACE, AND ALEXANDER ARNOIS, OF PHILADELPHIA, PENNSYLVANIA.

METHOD OF CONTROLLING HIGH-TENSION CURRENTS.

SPECIFICATION forming part of Letters Patent No. 628,026, dated July 4, 1899.

Application filed October 15, 1898. Serial No. 693,683. (No model.)

To all whom it may concern:

Be it known that I, HENRY GIBSON O'NEILL, a subject of the Queen of Great Britain, and a resident of New York, in the county of New York and State of New York, have invented certain new and useful Improvements in Methods of Controlling High-Tension Currents, &c.; and I do declare the following to be a full, clear, and exact description of the invention, such as will enable others skilled in the art to which it appertains to make and use the same, reference being had to the accompanying drawings, and to letters of reference marked thereon, which form a part of this specification.

Figure 1 of the drawings is a side elevation of the invention, partly broken away. Fig. 2 is a section on line xx , Fig. 1. Fig. 3 is a side elevation of a modification of the invention.

This invention relates to the art of controlling currents of electricity, and is especially designed to supply a convenient method of and apparatus for regulating high-tension currents.

The principle involved consists in interposing in circuit the resistance offered by a vacuum and a wall of glass, thereby obtaining not alone any desired reduction in electro-motive force, but also such attenuation of the current as to permit its use in a flattened-out form with a mild effect, resembling a shower of minute feathers.

In the accompanying drawings, A represents a tube of glass having a terminal A' sealed therein, air having been previously withdrawn from said tube. The degree of vacuum and thickness of the walls of the tube is regulated according to the circumstances of voltage and desired effect.

B represents a metallic ring having spring-contacts B', adapted to slide along and engage the walls of the tube. On the exterior of this ring there is a rubber or other non-conducting handle B² or means of holding same for the purpose of sliding the ring along the tube, said ring also having a binding-post B³ or other suitable means for attaching a conductor, by which connection is made to the point of utilization. As the ring is moved more or less remote from the terminal that enters the vacuum-chamber, it is obvious that the voltage is increased or diminished. It

will be observed, therefore, that the operation consists in taking the current into the tube at the terminal A' and passing the same through any desired degree of vacuum, depending upon the distance of the ring B from the terminal, and tapping the current off through the walls of the glass by the metallic ring through the contact-springs B'.

It is obvious that the shape of the tube, whether straight, curved, or circular, is immaterial. I employ but one wire to my circuit. While the foregoing is the form I find most convenient, variations of this will present themselves. For carrying out the same principle various contact-points may be sealed into the tube and enter the vacuum-chamber at varying distances throughout its length. Such arrangement would in the main admit of obtaining variations of voltage, though hardly the perfect regulation that may at times be necessary or desired.

What I claim as new, and desire to secure by Letters Patent, is—

1. The method of controlling high-tension currents, which consists in passing the same through a terminal into a sealed-in glass tube or closure, from which air has been withdrawn, and tapping them off at different distances from the terminal, by a metallic contact, through the walls of the glass tube, the voltage being regulated by the length of vacuum interposed.

2. The means for regulating high-tension currents, which consists of a glass tube or closure from which air has been withdrawn; a terminal electrode sealed in said tube or closure; and adjustable means for tapping off the current, as and for the purposes set forth.

3. In a rheostat for high-tension currents, the combination of a glass tube or closure from which air has been exhausted; a metallic electrode or electrodes sealed in said tube or closure; and a metallic piece adapted to closely engage the exterior walls of the tube or closure, substantially as specified.

In testimony whereof I affix my signature in presence of two witnesses.

HENRY GIBSON O'NEILL.
